ATTORNEY

UNITED STATES PATENT OFFICE

HARRY HIRSCHFELD, OF SEA CLIFF, NEW YORK

RUBBER HEEL

Application filed July 8, 1931. Serial No. 549,532.

This invention relates to rubber heels and it has for one of its objects the provision of a rubber heel having embedded therein a wear-resisting plate.

5 Another object of the invention is the provision of a rubber heel embodying a wear-resisting plate of novel construction, which is preferably resilient and which preferably is provided with retaining lugs of novel construction, said lugs being also preferably resilient and extending at an angle to the plate.

A further object of my invention is the provision of a rubber heel having incorporated therein a wear-resisting plate adjacent the rear edge and the lower surface of the heel so that the heel will be worn uniformly.

Other objects of the invention will be appreciated from a reading of the following 20 specification.

The invention will be fully and comprehensively understood from a consideration of the following detailed description when read in connection with the accompanying 25 drawing which forms part of the application, with the understanding, however, that the improvement is capable of extended application and is not confined to the exact showing of the drawing nor to the precise construction described and, therefore, such changes and modifications may be made therefrom as do not affect the spirit of the invention nor exceed the scope thereof as expressed in the appended claims.

30 In the drawing:

Fig. 1 is a plan view of my improved rubber heel.

Fig. 2 is a section taken on line 2—2 of Fig. 1.

40 Fig. 3 is a vertical section taken on line 3—3 of Fig. 1.

Fig. 4 is a perspective view of the wear-resisting plate shown in Figs. 1, 2 and 3, as embedded in a rubber heel; and

45 Fig. 5 is a vertical section similar to Fig. 2, but showing a modified form of wear-resisting plate embedded in the rubber heel.

Referring to the drawing for a more detailed description thereof, the numeral 7 indicates a rubber heel of any usual or pre-

ferred construction. Adjacent the rear edge and the lower surface of the heel, a wear-resisting plate 8 is embedded in the heel. The mentioned plate is preferably a metal plate and is preferably resilient and corrugated, the resiliency being increased by the corrugations. Portions 8a of the corrugated plate, as shown in Fig. 1, are flush with the lower surface of the rubber heel while the intervening portions 8b are above the mentioned lower surface. The metal plate is curved to conform with the curvature of the rubber heel and it has, extending from the inner side thereof, a plurality of tapered retaining lugs 9, said lugs being bent upwardly at an angle to the plate and therefore being more deeply embedded in the rubber heel than the plate itself. The mentioned lugs 9 are preferably resilient. The resiliency of the mentioned lugs and their angularity relative to the plate are effective to resiliently mount the plate, independent of the fact that the plate is embedded in rubber. The mentioned plate is also provided with end lugs 10, these lugs also being preferably resilient and bent upwardly from the lower surface of the heel, the heel being regarded as attached to a shoe, and the shoe in normal position. The lugs 10 are thus, like the lugs 9, embedded more deeply in the heel than is the plate. The lugs 9 and 10 are provided, respectively, with apertures 9a and 10a so that the rubber, when in the plastic state, may flow therethrough and, when solidified, securely hold the lugs, and therefore the plate, in position.

The modified form of the invention shown in Fig. 5 is similar to the form previously described except that the end lugs 12 are bent inwardly towards each other in a direction parallel to the upper and lower surface of the heel, being spaced from the wear-resisting plate 8.

What is claimed as new is:

1. A rubber heel comprising a rubber body and a metal plate interior thereto, the said plate being arranged adjacent the rear edge of the heel and extending substantially parallel to the tread face and being generally of corrugated form with the peaks of the cor-

rugations extending to said tread face of the heel.

2. A rubber heel comprising a rubber body and a metal plate interior thereto, the said plate being arranged adjacent the rear edge 5 of the heel and extending substantially parallel to the tread face and being generally of corrugated form with the peaks of the corrugations extending to the surface bearing face of the heel, said plate being provided with 10 retaining lugs extending into the rubber body in a direction away from said tread face.

3. A rubber heel comprising a rubber body and a metal plate interior thereto, the 15 said plate being arranged adjacent the rear edge of the heel and extending substantially parallel to the tread face and being generally of corrugated form with the peaks of the corrugations extending to said tread face of 20 the heel, said plate being resilient and formed with anchoring lugs at its extremities and on one side edge adjacent the peaks of the corrugations.

25 In testimony whereof I hereby affix my signature.

HARRY HIRSCHFELD.
